UNITED STATES PATENT OFFICE.

AMOS M. CARPENTER, OF KALAMAZOO, MICHIGAN.

EXPANDED METAL.

1,188,729.

Specification of Letters Patent. Patented June 27, 1916.

Original application filed July 7, 1913, Serial No. 777,646. Divided and this application filed February 25, 1915. Serial No. 10,552.

To all whom it may concern:

Be it known that I, AMOS M. CARPENTER, a citizen of the United States, residing at 919 North Church street, in the city and county of Kalamazoo, State of Michigan, have invented certain new and useful Improvements in Expanded Metal, of which the following is a specification.

This invention relates to improvements in expanded metal and process of making the same.

The main objects of this invention are: first, to provide an improved expanded metal; second, to provide an improved method or process of making expanded metal.

Further objects, and objects relating to structural details, will definitely appear from the detailed description to follow.

I accomplish the objects of my invention by the devices and means described in the following specification.

The invention is clearly defined and pointed out in the claims.

A structure which is a preferred embodiment of my invention is clearly illustrated in the accompanying drawing forming a part of this specification, in which:

Figure I is a blank slotted showing the first step of the process of producing my improved expanded metal. Fig. II is a detail plan view of a section of an expanded metal, embodying the features of my invention. Fig. III is a detailed transverse section on a line corresponding to line 3-3 of Fig. II. Fig. IV is a detailed inverted perspective of the reinforcing member. Fig. V is a detailed inverted perspective view of a modified form of the reinforcing member.

In the drawings similar reference characters refer to similar parts throughout the several views, and the sectional views are taken looking in the direction of the little arrows at the ends of the section lines.

Referring to the lettered parts of the drawing: My improved expanded metal comprises spaced longitudinal bars 1 with open or expanded work between. The expanded work comprises a plurality of continuous longitudinal strand members 2 and connecting or tie members 3. Each tie member is united at one end to one of the strand members 2 or one of the bar members 1 and at the other end to an adjacent tie

member. The tie members upon opposite sides of the strand members are alternately arranged, the points of union of the tie members to the strand members being substantially spaced so as to permit the bending of the strands between such union points. The other end of each tie member is united to an adjacent tie member between and at a point substantially spaced from its points of union to the tie member and strand member to which it is in turn connected so as to permit the bending of the tie members between such union points. The tie members and strand members in the structure illustrated are of uniform and substantially the same width. This is desirable where uniform openings in the open or expanded work is desired.

The structure illustrated is provided with longitudinal bars 1 spaced but a short distance apart. These bars may be spaced as desired or may be entirely omitted. If the strands 2 are of substantially the same width as the ties 3 as in the structure illustrated they will be uniformly distorted by the expansion but if of sufficiently greater width than the tie members they will remain straight or substantially straight.

In producing my improved expanded metal the sheet of metal is first slit as shown in the blank 4, Fig. I, and consists of forming a plurality of double series of aligned spaced slits 5, the slits of one series being alternately disposed relative to those of the other. Between the double series of slits 5 is an intermediate series of short slits 6, one end of each intermediate slit being disposed opposite corresponding ends of the alternate slits of the double series. Cross slits 7 are formed connecting such opposite ends of the slits 5 and 6.

Portions between the double row of slits have no cross slits, and constitute the strands 2. The parts between the ends of the slits 5 and 6 constitute the union parts 8 of the ties, while the parts between the ends of the slits 5 constitute the union parts 9 for uniting the tie members to the strand members 2 or for uniting the tie members to the bar members 1.

After slitting as shown the expansion is effected by drawing laterally which causes the slits to open and the ties and strands to assume an inclined position as indicated in Figs. II and III.

The tie members and strands being joined as described causes them to take a curved form and swing edgewise to the plane of the sheet of which they are formed as shown in 5 the drawing. This form and position is highly desirable in receiving and retaining plaster.

Owing to the manner of joining the strands and tie members their points of 10 union are not likely to tear or break during the expanding operation or when subjected to blows or bending or other stresses in handling or use. By this process expanded metal may be very economically produced 15 and the parts are connected so as to effectively withstand the stresses of expanding and handling and using.

In Fig. IV, I show an improved reinforcing member 10 formed of sheet metal and 20 having fingers 11 struck down at its edges and adapted to be engaged under the strands and tie members as shown in Fig. II. The reinforcing member being arranged transversely across the bars 1 and the ties and 25 strands, braces and supports the open work so that it is very rigid and well adapted for the purposes for which it is designed.

In the modified structure shown in Fig. V the reinforcing member 10 is provided with 30 a single row of fingers 11 and reinforcing ribs 12 at each side.

The form shown in Fig. IV has a single reinforcing longitudinal rib 12 between the fingers 11.

35 My improved expanded metal is well adapted for embodiment in wall structures such as shown in my application for Letters Patent, filed July 7, 1913, Serial No. 777,646, of which the present application is a division. It is however desirable for use in the other relations as expanded metal lath and the like.

Having thus described my invention, what I claim as new and desire to secure by Letters Patent is:

1. An expanded metal structure of sheet metal comprising spaced bars and a connecting open work comprising strand members and tie members, each tie member being 50 united at one end to a strand or bar, the tie members on opposite sides of the strand members being alternately disposed, their points of union thereto being spaced so as to permit the bending of the strands between 55 such union points, the other ends of the tie members being connected to an adjacent tie

member between and at a substantial distance from such tie member points of union with the strands or bars and tie members so as to permit the bending of the tie members 60 between such union points to which its ends are united, the tie members and strands being of substantially the same width.

2. An expanded metal structure of sheet metal comprising spaced bars and a connecting open work comprising strand members and tie members, each tie member being united at one end to a strand or bar, the tie members on opposite sides of the strand members being alternately disposed, their 70 points of union thereto being connected to an adjacent tie member between and at a substantial distance from such tie members points of union with the strand or bar and tie member to which its ends are united so 75 as to permit the bending of the strands and ties between said points of union.

3. An expanded metal structure comprising continuous strand members and tie members, each tie member being united at one 80 end to a strand member and at the other end to an adjacent tie member between and at substantial distances from its points of union with the tie member and strand to which its ends are united, the tie members 85 on opposite sides of the strand members being alternately disposed, their points of union with the strands being spaced so as to permit the bending of the strands between such union points, the tie members and 90 strands being of uniform and substantially the same width.

4. An expanded metal structure comprising continuous strand members and tie members, each tie member being united at one 95 end to a strand member and at the other end to an adjacent tie member between and at substantial distances from its points of union with the tie members and strand to which its ends are united, the tie members 100 on opposite sides of the strand members being alternately disposed, their points of union with the strands being spaced so as to permit the bending of the strands between such union points.

In witness whereof, I have hereunto set my hand and seal in the presence of two witnesses.

AMOS M. CARPENTER. [L. s.]
